CLAIM

The ornamental design for strap for goggles, as shown and described.

DESCRIPTION

FIG. 1 is a top, rear and right side perspective view of a strap for goggles of our design.

FIG. 2 is rear view thereof.

FIG. 3 is a left side view thereof.

FIG. 4 is a right side view thereof; and,

FIG. 5 is a second right side view showing the strap for goggles in use thereof.

Elements drawn in broken lines represent environmental features of the goggles that form no part of the claimed design for the strap for goggles.

1 Claim, 5 Drawing Sheets
